UNITED STATES PATENT OFFICE

JESSE MIDDLETON PAYNE AND LEWIS WALKER HODGE, OF PHENIX CITY, ALABAMA

THREAD HOLDER.

Application filed October 15, 1928. Serial No. 312,700.

The present invention relates to looms for weaving cloth, and has particular reference to an improved holder for the threads which are left on the selvage edges of the cloth, so that the temple may cut such threads.

Heretofore, no satisfactory means or method has been found to cut the threads on the left hand or box side of the loom, although successful devices have been utilized for cutting the threads on the right hand side of the cloth.

It is therefore the prime purpose of the present invention to provide an improved holder and operating means therefor to accomplish the object of cutting the threads on the left hand or box side of the loom.

Another object of the invention is to provide an improved holder for use in connection with a left hand temple cutter which operates in the regular manner so that the device is in the form of an attachment which may be applied to looms already constructed and which are being manufactured according to the present construction.

The improved holder holds the thread after the temple has cut the thread apart from side of the cloth by the regular method, and continues to perform its function for all changes that take place in filling threads and enables the temple to cut thread close to selvage of the cloth; thus saving the time heretofore used in cutting off threads by hand as well as the loss of material where the singeing method is used instead of cutting off by hand. The improved holder works in connection with the box change and performs its duty just as accurately, and is actuated by the same chain that works boxes to put in the various fillings.

The invention further aims at the provision of a temple cutter, holder and operating mechanism therefor which is adapted to save the labor formerly used in cutting or singeing off threads on the box side of the selvage, as well as the saving of material hitherto lost by singeing, also saving the yarn which is used up in the usual method by the yarn following along the selvage until it is again used for filling.

The invention also aims to provide a device

of this character which eliminates all waste on the selvage of the loom and which heretofore was a total loss as this waste has to be either singed or cut off with scissors by hand, an operation which is very expensive as well as very trying on the hands who had to use scissors in clipping this thread from the selvage of the cloth.

Other objects and advantages will be apparent from the following description when considered in connection with the accompanying drawings and will be more particularly pointed out in the appended claims.

In the drawings;

Figure 1 is a top plan view of a thread-cutting temple constructed according to the present invention, the dotted lines showing the adjacent supporting parts of a loom.

Figure 2 is a side elevation of the same, the parts being in one position.

Figure 3 is a like view showing the part in a second position.

Figure 4 is a right-hand end elevation of the device.

Figure 5 is a left-hand end elevation of the same.

Figure 6 is a detail enlarged longitudinal section taken through the improved holder.

Figure 7 is a side elevation of the holder in a reversed position to that shown in Figure 6.

Figure 8 is a forward end view of the holder looking at the right-hand end of Figure 7, and,

Figure 9 is a transverse section taken through the holder substantially on the line 9—9 of Figure 6, and looking in the direction of the arrows.

Referring now to the drawings, 15 designates the selvage edge of cloth being woven, the same being shown in dotted lines, 16 shows a conventional temple cutter in dotted lines and which is provided with cutting jaws 17. The holder of this invention is located opposite to the temple cutter 16, and is constructed as follows: The holder has an arm 18, best shown in Figures 6 to 9, and which projects rearwardly in a vertically edgewise position, and which at its rear end projects downwardly at an angle and is provided near

its lower edge portion with a laterally extending fixed jaw 19.

As shown in Figure 1, the thread 20 which extends from the selvage edge 15 of the cloth being woven, passes over the face of the jaw 19 and through a guide notch 21 in the rear edge of the arm 18 and which is disposed opposite to the jaw 19. The arm 18 carries a side plate 22 which is located at the side 5 of the arm 18 from which the fixed jaw 19 projects. This side plate 22 is provided at its inner side and near its rear end with a bushing which constitutes a spacer as shown at 23 for holding the plate 22 in desired 10 spaced relation from the side of the arm 18. A machine screw 24 or the like engages through the arm 18 and into the spacer 23 for securing the parts together in the form 15 of a frame. A yielding or movable jaw 25 is disposed between the arm 18 and the side plate 22, and is pivotally mounted at its forward end upon a pin 26 which is secured to the arm 18 and the side plate 22. The jaw 25 is normally urged downwardly by 20 a spring 27 which is interposed between the spacer 23 and the jaw as shown in Figure 6.

Between the arm 18 and the side plate 22, and forwardly of the pin 26, is a retaining lever 28, which is pivoted at its upper end 30 upon a pin 29 and which has its upper end adjacent to the pin 29 curved rearwardly and upwardly so as to offset the upper end of the lever 28. The retaining lever 28 is also provided, at its bend or angle portion, with 35 a lug 30 which projects forwardly from the lever 28 substantially opposite to the upper end thereof.

The rear forward end of the lug 30 is 40 pivotally connected to a headed or shoudered rod 31 which is mounted at its forward end in an upturned guide flange 32 of a bracket 33. The rod 31 is provided with a coil spring having one end bearing against the head of the rod and with its 45 other end engaging the guide flange 32 of the bracket so as to normally urge the rod 31 rearwardly and thus yieldingly hold the lug 30 in its raised and lowered positions.

To the lower end of the retaining lever 50 28 is pivotally mounted the forward end of a thread catching loop or hook 35, the same being pivotally mounted on a pin 36 carried upon the retaining lever 28. The hook 35 is in the form of a double hook and may 55 be constructed of a single piece of sheet metal which is folded over upon itself at its forward end and which has parallel arms which project rearwardly for engagement at the opposite sides of the movable jaw 25. The 60 forward closed end of the hook is curved downwardly beyond the retaining lever 28 and provides front and rear abutting shoulder for operating the hook. The rear shoulder 37 is relatively high and curved and 65 disposed substantially opposite to the pin

36, while the forward shoulder 38 is curved on a relatively long radius and extends downwardly beyond the retaining lever 28 and terminates at the lower end of the hook 35. The bills 39 of the hook 35 open downwardly 70 and are adapted to slide in grooves or ways 40 which are formed in the upper face of the fixed jaw 19 at opposite sides of the movable jaw 25.

From Figure 8 it will be noted that the 75 movable jaw 25 is of less width than the space between the arm 18 and the side plate 22 so as to provide guideways or recesses at opposite sides of the movable jaw 25 for the reception of the spaced arms of the 80 hook 35.

The bracket 33 is provided at its rear end 85 with an upstanding slotted guide flange 41 through which the forward end of the arm 18 slideably passes so that the arm 18 may move forwardly under pressure. The outer extremity of the arm 18 is headed to limit the rearward projection of the arm through the guide flange 41 and is also provided with a guide rod 42 which slideably engages 90 through the forward guide flange 32 of the bracket. A spring 43 is mounted on the rod 42 and bears at one end against the guide flange 32 and at its other end against the head on the forward end of the arm 18 so as to normally project the arm 18 rearwardly 95 from the bracket. The bracket 33 is provided, at a point between the guide flanges 32 and 41 with a longitudinal slot 44 through which engage headed set screws 45 secured in a bracket plate 46. The bracket plate 46 extends transversely beneath the bracket 33 and is provided with a rearwardly and downwardly inclined bearing face upon 100 which the bracket 33 rests. The bracket plate 46, Figure 1, is provided with an attaching lug 47 for receiving a screw 48 for 105 adjustably mounting the bracket plate on the base plate 49 carried on the breast beam 50 of the loom.

The holder thus described is so mounted 110 upon the loom, as shown in Figure 1, that the lay beam 51 operates toward and from the rear end of the holder. A suitably shaped thread guide 52 is mounted on the lay 115 inwardly of the holder and is adapted to receive the thread 20 at the side of the holder opposite to the temple cutter 16. It will be noted that the thread guide 52 has its arms flaring or diverging rearwardly with one arm disposed above the other so as to catch and hold the thread and permit of the movement of the lay beam 51 without losing the thread 20. The lay beam 51 is disposed substantially in line with the rear shoulder 37 120 of the hook and as the lay beam 51 approaches the end of its forward stroke it strikes the shoulder 37 and actuates the hook 35.

For the purpose of tripping the hook 35 rearwardly, by operation of the box change 125

mechanism, a bearing bracket 53 is mounted on one side of the loom frame 54 and a rocker shaft 55 is mounted in the bracket 53 with one end extending beneath the holder. The 5 inner end of the rocker shaft 55 is provided with a trip arm 56 which extends upwardly and has a curved upper end adapted to engage the forward shoulder 38 of the hook 35. The outer end of the rocker shaft 55 is provided with an upstanding arm 57 pivotally connected at its upper end to a connecting rod 58 suitably bent or shaped to avoid contact with the adjacent parts of the loom and which at its other end is pivotally connected to an arm 59 of a bell crank lever, the arm 59 extending upwardly and normally inclined forwardly to a slight degree. The other arm of the bellcrank lever extends downwardly and forwardly, in normal position, and is pivotally connected at its lower end to a vertical rod 60. A bracket 61 is secured to the loom frame 54 and pivotally supports the bellcrank lever 59.

The vertical rod 60 is provided at its upper end with an adjustable coupling head 62 which has pivotal and rocking engagement with the outer end of a cam lever 63 pivotally mounted at its outer end upon bracket arms 64 or the like. The intermediate portion of the lever 63 is provided with a downwardly extending cam 65 the shoulder of which faces toward the inner or pivoted end of the lever 63 and lies in the path of a travelling cam 66 mounted on the chain 67 which 25 operates the box change mechanism. The travelling cam 66 may be in the form of a link inserted in the chain 67 so as to be operated thereby in predetermined timed relation for engaging the cam 65 under lever 35 63.

From the above description it is thought that the operation of the machine as applied to a loom will be clearly understood. Briefly stated, when the chain 67 travels sufficiently 40 to bring the cam 66 beneath the cam 65 of the lever 63, the interengagement of the cam lifts the free end of the lever 63 and draws the vertical rod 60 upwardly with the result that the bellcrank lever 59 is rocked and 45 the connecting rod 58 is shifted to actuate the rocker shaft 55. This movement of the rocker shaft 55 brings the free end of the trip arm 56 against the forward shoulder 38 of the hook 35. The hook 35 is uplifted 50 or swung upwardly on its pin 36 to free the thread 20 and the hook 35 is also projected rearwardly from the holder arm 18, swinging the lever 28 rearwardly at its lower end and bringing the lug 30 beneath the longitudinal axial line of the pivot 29 so that 55 the spring 34 comes into play for yieldingly holding the hook 35 in a rearwardly projected position.

During this forward projection of the hook 60 35, the lay beam 51 is moved away from the

holder so that the thread guide 52 carries the thread 20 therewith. As soon, however, as the lay beam 51 beats up toward the holder, the thread 20 is carried into the region of the holder and the beam 51 toward the end 70 of its inward stroke strikes against the front shoulder 37 of the hook with the result that the hook is not only swung downwardly about its pivot 36, but that the lever 28 is swung rearwardly at its lower end and upon its pin 29. This action thus drops the hook 35 downwardly into the lower fixed jaw 19 and causes the hook to engage the thread 20 and pull it into position between the fixed jaw 19 and the upper movable jaw 25. At 75 this time, the lug 30 is swung upwardly beyond the horizontal axis of the pin 29 and the spring 34 yieldingly holds the lever 28 in this new backward position. It will be noted that when the temple 16 cuts the thread, the improved holder will hold that thread for the various operations of the box and other cooperating parts of the loom. 80

What we claim is:

1. In combination with a loom having a lay beam and a box change mechanism, a temple cutter adapted to be mounted at the left side of the loom, a holder spaced from the temple cutter adapted to receive thread therefrom to hold the thread during the box operation, a hook slideably and pivotally mounted on the holder, a shouldered portion carried by the hook lying in the path of said lay, said lay adapted to engage one shoulder of said projection for swinging the hook downwardly and forwardly to catch and carry a thread into the holder, a rocker shaft mounted on the loom, a pivoted lever carried by the loom and having a depending cam portion, connections between said lever and said rocker shaft for moving the latter when the lever is raised, a travelling cam adapted for connection with the box change mechanism for intermittently engaging said lever to rock the shaft, and a trip arm carried by the shaft adapted to engage said hook for projecting the same forwardly and swinging the same upwardly preparatory to catching a thread. 100

2. In combination with a loom having a temple cutter at the left hand side thereof, a lay beam and a box change mechanism, a bracket adjustably mounted on the loom adjacent to the temple cutter, an arm yieldably mounted on the bracket, a hook pivotally and slideably mounted on the arm and having a shouldered projection depending below the arm, said projection lying in the path of said lay beam and adapted to be engaged thereby for swinging the hook downwardly and rearwardly, a bracket mounted on the frame of the loom, a rocker shaft mounted in said bracket and having a trip arm lying in the path of said shouldered projection, a second arm on the rocker shaft, a lever pivoted to 110

the loom frame adjacent the box changing mechanism, a connection between said lever and said arm of the rocker shaft, and a cam connected to the box change mechanism for engagement with said lever to swing the same and actuate said rocker shaft.

3. A holder of the character described, comprising an arm, means for yieldingly supporting said arm, said arm having a fixed jaw, a yielding jaw mounted on said arm for cooperation with a fixed jaw to hold a thread between the jaws, a hook pivoted to said arm, said hook having a bill on its rear end adapted to register with said jaws, said hook adapted for movement lengthwise of the arm and adapted to swing about its pivotal connection with the arm, and means connected to said hook for yieldingly holding the same in projected and retracted positions.

20 4. A holder as specified comprising a bracket, an arm yieldably mounted on the bracket, a T-shaped lever pivotally mounted at one of its branches on said arm, a hook pivotally mounted on the free end of the 25 shank of said lever, a yielding connection pivoted to the other branch of said lever for yieldingly holding the lever in oppositely swung positions, guiding means for said hook, and a pair of jaws carried by the arm 30 in registry with said hook adapted to receive thread engaged by the hook.

5. A holder as specified comprising a yieldably mounted frame, a fixed jaw in the arm, a yieldable jaw on the arm cooperating with 35 a fixed jaw to hold a thread between the jaws, a double hook having a portion lying at opposite sides of the jaws, means for pivotally supporting said double hook, said supporting means being mounted for movement on the 40 arm lengthwise of the latter, and means for yieldingly holding the double hook in projected and retracted positions.
